UNITED STATES PATENT OFFICE.

WILLIAM WILSON, OF GENEVA, NEW YORK.

ROADWAY.

SPECIFICATION forming part of Letters Patent No. 748,248, dated December 29, 1903.

Application filed June 12, 1903. Serial No. 161,145. (No model.)

To all whom it may concern:

Be it known that I, WILLIAM WILSON, a citizen of the United States, residing at Geneva, Ontario county, New York, have invented certain new and useful Improvements in Roadways, of which the following is a specification.

The object of my invention is to provide an improved roadway which shall have all the advantages of the well-known Telford and tarred Macadam roadways and which shall overcome many of the objections to both.

The invention consists of a roadway having a layer of comparatively large irregularly-shaped stones laid adjacent to each other with one broad flat face of each lowermost, having the upper surfaces of said stones coated with a bituminous substance, having the apices of the angular spaces between said stones filled with a mixture of a bituminous substance with sand and stone screenings, tamped in place, and having the remaining portions of the spaces between said stones filled with tarred macadam material, consisting of stones coated or mixed with a bituminous substance, the said macadam material being subjected to compression to force and hold the same in place.

The invention also consists in the novel method of laying the roadway, as will be more fully hereinafter described and claimed.

In the drawing forming part of this specification the figure thereof is a cross-sectional view of a portion of a roadway constructed in accordance with my invention.

In carrying out my invention the road-bed 1 is formed by suitably grading the earth between the curbs, and on this bed is placed by hand a layer of comparatively large stones 2, varying somewhat in size from six to twenty inches in length, from four to eight inches in width, and from six to ten inches in height. These stones are taken just as they come from the quarry, and each is laid on the bed with one of its flat sides lowermost. Afterward, each of the stones 2, which go to make up the foundation layer, is coated with tar or other bituminous substance, as indicated by the numeral 3. This bituminous substance may be applied either by sprinkling the same on said stones or by sweeping it thereon through the agency of a broom. When the stones 2 have been laid as described, the

apices of the angular spaces 4 between them are filled with a mixture of tar or other bituminous substance and sand, stone screenings, or the like, which mixture is carefully tamped into place. When this has been done, the remaining portions of the spaces between said stones are filled with tarred macadam material—that is, a mixture of broken stones, preferably from one-half inch to two and one-half inches in size, and tar or other bituminous substance, together with a substance such as sand, stone-dust, or screenings. This material constitutes a filler 5 and extends up to a point 55 in line with or slightly above or below the tops of the stones 2. The same is tamped into place and afterward it is further compressed, as by passing a heavy roller over the same. The rolling process will cause slight depressions to be formed between the tops of the adjacent stones 2, but tends to thoroughly and completely compact the mass between said stones. When the rolling operation has been effected, a layer 6 of tarred macadam 60 material exactly the same as the material 5 is placed upon the upper surface of the roadway as thus far completed and is thoroughly rolled and compacted. The result is that the upper surface of the roadway will be evenly 65 arched or leveled with no danger of the formation of pockets or recesses for the reception of water afterward. A thin top dressing 7 of a bituminous substance mixed with sand, stone screenings, or the like may be laid upon 70 the upper surface of the layer 6 for the purpose of forming a smooth and finished condition to the upper surface of the completed 75 roadway.

It has been stated heretofore that the filler 80 5 of tarred macadam material is composed of comparatively small stones mixed with tar or other bituminous substance and sand, stone-dust, or screenings. I do not limit myself, however, to any particular size of stones 85 or even to small stones. Large stones coated or mixed with a bituminous substance may be employed, inserted into the spaces between the stones 2 of the foundation. The filler 90 made of the large stones need not come up to the tops of the stones 2, or it may project 95 above the same. The large stones of which the filler is made may be placed in position 100 by hand or by other means; but all the spaces

between the same and the sides of the stones 2 should be filled either with a very fine tarred macadam material or with the same substance that is employed in filling the apices of the 5 angular spaces 4.

The coating of the stones 2 with the layer 3 of tar or other bituminous substance serves to effect a complete and lasting bond between said stones and the tarred macadam filler 5. 10 Furthermore, as the stones 2 are laid with one flat face of each lowermost the danger of the sinking of the road-foundation into the road-bed is reduced to a minimum. Lateral separation of the stones 2, which constitute 15 the foundation, is prevented by the filler 5 of tarred macadam material, and the said filler 5 also serves to build up and form a stable and reliable body for the road. The fine tarred macadam material is used in the 20 apices of the angular spaces 4 in order to insure a complete filling of said spaces. If the ordinary tarred macadam material of which the filler 5 is made were employed for this purpose, it would in many cases be prevented 25 from penetrating to the extreme lower ends of said spaces by reason of the fact that the stones which form part of said material are too large.

Having now described my invention, what 30 I claim as new, and desire to secure by Letters Patent, is—

1. A roadway having a layer of comparatively large irregularly-shaped stones laid adjacent to each other with one broad flat face 35 of each lowermost, having the upper surfaces of said stones coated with a bituminous substance, having the apices of the angular spaces between said stones filled with a mixture of a bituminous substance with sand and stone 40 screenings, tamped in place, and having the remaining portions of the spaces between said stones filled with a tarred macadam material, consisting of stones coated or mixed with a bituminous substance, the said macadam ma-

terial being subjected to compression to force 45 and hold the same in place.

2. The method of laying a roadway, which consists in placing a layer of comparatively large irregularly-shaped stones upon a suitable bed, with one broad, flat face of each 50 lowermost, coating the upper surfaces of said stones with a bituminous substance, filling the apices of the angular spaces between said stones with a mixture of a bituminous substance with sand or stone screenings, and 55 tamping it into place, filling the remaining portions of the spaces between said stones with tarred macadam material, consisting of stones coated or mixed with a bituminous substance, and subjecting said tarred ma- 60 cadam material to compression.

3. The method of laying a roadway, which consists in placing a layer of comparatively large irregularly-shaped stones upon a suitable bed, with one broad, flat face of each 65 lowermost, coating the upper surfaces of said stones with a bituminous substance, filling the apices of the angular spaces between said stones with a mixture of a bituminous substance with sand or stone screenings, and 70 tamping it into place, filling the remaining portions of the spaces between said stones with tarred macadam material, consisting of stones coated or mixed with a bituminous substance, tamping and rolling down said tarred 75 macadam material, placing a layer of the same material on top of that previously laid, rolling the latter layer down into place, and finally applying a top dressing or surface coating to complete the roadway. 80

In testimony whereof I have hereunto set my hand in presence of two subscribing witnesses.

WM. WILSON.
